DESIGN FOR AN ALTAR

Lawrence J. Murphy, Brooklyn, N. Y.

Application January 9, 1942, Serial No. 105,083

Term of patent 7 years

To all whom it may concern:

Be it known that I, Lawrence J. Murphy, a citizen of the United States and resident of Brooklyn, New York, in the county of Kings and State of New York, have invented a new, original, and ornamental Design for an Altar, of which the following is a specification, reference being had to the accompanying drawing, forming a part thereof,

In the drawing:

Fig. 1 is a front elevational view of an altar, showing my new design.

Fig. 2 is a side elevational view of the same.

Fig. 3 is a top plan view of the same.

I claim:

The ornamental design for an altar, as shown.

LAWRENCE J. MURPHY.
